No. 613,655.

Patented Nov. 8, 1898.

J. P. BEARDALL.

REGISTRY CHART.

(Application filed May 18, 1898.)

(No Model.)

FIG. 1.

FIG. 2.

UNITED STATES PATENT OFFICE.

JOHN P. BEARDALL, OF NEW YORK, N. Y.

REGISTRY-CHART.

SPECIFICATION forming part of Letters Patent No. 613,655, dated November 8, 1898.

Application filed May 18, 1898. Serial No. 681,048. (No model.)

To all whom it may concern:

Be it known that I, JOHN P. BEARDALL, a citizen of the United States, residing at New York, (Brooklyn,) in the county of Kings and State of New York, have invented certain new and useful Improvements in Registry-Charts or Keyboards, of which the following is a full and complete specification, such as will enable those skilled in the art to which it appertains to make and use the same.

This invention relates to registry-charts or keyboards for use by real-estate agents in order to properly classify and arrange the property under their control; and the object there-
15 of is to provide an improved device of this class which is adapted to be used in connection with city, county, or State maps showing the location or position of said property.

The invention is fully disclosed in the following specification, of which the accompanying drawings form a part, in which—

Figure 1 is a front view of my improved registry-chart or keyboard, and Fig. 2 a side view thereof.

25 In the practice of my invention, as shown in the drawings, I provide a registry-chart or keyboard 5, which is preferably divided centrally by a vertical line 6, and at the top thereof is placed the name of the real-estate agent or firm. The spaces formed by the vertical line 6 contain certain headings relating briefly to the real estate under the control of the agent or firm, and these headings, as shown in the drawings, are substantially as follows, refer-
30 ring to the left-hand space: The left-hand space is provided at the top thereof with the heading "For sale—houses, lots, farms, &c.," and underneath this are placed the separate headings "Brick houses," "Frame houses,"
35 "Lots and plots," "Exchanges," and "Farm-houses" and others, and the right-hand space is provided at the top with the heading "To let—houses, stores, floors, &c.," and underneath this is the separate heading "Frame houses, (and this heading is preferably repeated,) and below the same are the headings "Flats and floors," "Miscellaneous, repair-
40 ing wanted," and others.

Under the heading "Brick houses" in the 50 left-hand column are placed numerals representing the prices of the houses under this heading, and beneath these numerals are

placed two rows of pins 7, and similar numerals and pins are placed under the heading "Frame houses" and under the heading 55 "Lots and plots" and under the heading "Ex-
changes," and under the heading "Farms for sale" is placed the number of acres contained in each lot or piece of ground, and beneath the heading "Keys" are also placed numerals 60 from "1" to "200," and pins 7 are arranged under each of these headings the same as under the first, and similar arrangement is fol-
lowed in the left-hand space, and at the bottom of the chart or keyboard is the heading 65 "Special bargains in real estate for sale," beneath which are placed numerals represent-
ing the wards in the city or town in which the agent is located.

Under the old system the records are kept 70 in books containing the names of the owners and a description of the property, said names being arranged in alphabetical order, and these records often become confused; but under my improved system I employ city, county, 75 or State maps showing the location of all the property under the control of the agent, and the separate pieces of property are each desig-
nated on said charts or maps by a number, and a registry-book containing the names of 80 the owners of the property is also kept, to-
gether with a corresponding number found on said maps or charts, and these numbers are arranged in numerical order, and opposite each number is placed the name of the owner 85 of the particular piece of property to which the number refers. I also employ tags or cards, on one side of which is placed said num-
ber, and a chart or diagram showing the exact 90 location of the property, and on the other side 90 of said tag or card is placed a description of the property and the terms relating thereto, including the price, and if a brick house is for sale the price of which is three thousand dollars the tag or card bearing the informa- 95 tion referred to is suspended from the left-
hand pin 7 in the upper row under the head-
ing "Brick houses." The name may readily be determined by referring to the record-book, said name being designated by the number 100 found on the tag or card.

In the case of "Special bargains" in the separate wards of the city or town the card or tag is hung on the corresponding pin beneath

the number of the ward, and the same system is followed in connection with all the headings found on the chart or keyboard.

It will be apparent that the headings on the chart or keyboard may be modified to suit any circumstances, and my improved chart or keyboard may be used in any and all localities, as will be readily understood.

Having fully described my invention, I claim as new and desire to secure by Letters Patent—

A chart or keyboard for use by real-estate agents provided with a plurality of headings which designate the character of the property for sale or rent, and beneath which are placed

numerals which represent the price thereof, or give other information, said chart or keyboard being also provided beneath said numerals with a row or rows of pins from which a card or tag may be suspended, substantially as shown and described.

In testimony that I claim the foregoing as my invention I have signed my name, in presence of the subscribing witnesses, this 16th day of May, 1898.

JOHN P. BEARDALL.

Witnesses:
